UNITED STATES PATENT OFFICE.

CASWELL WATERS, OF PRYORCREEK, INDIAN TERRITORY, ASSIGNOR OF
ONE-HALF TO S. A. BYERS, OF PRYORCREEK, INDIAN TERRITORY.

DRIVING MECHANISM.

SPECIFICATION forming part of Letters Patent No. 770,879, dated September 27, 1904.

Application filed December 31, 1902. Serial No. 137,351. (No model.)

To all whom it may concern:

Be it known that I, CASWELL WATERS, a citizen of the United States, residing at Pryor-creek, Cherokee Nation, Indian Territory, have invented certain new and useful Improvements in Driving Mechanism; and I do declare the following to be a full, clear, and exact description of the invention, such as will enable others skilled in the art to which it appertains to make and use the same.

This invention relates to driving mechanism for fan-blower and other like machines; and it consists of the features of construction and combination of parts hereinafter described and claimed.

The invention is illustrated in the accompanying drawings, in which—

Figure 1 is a view in front elevation of a fan-blower machine, showing the application of the invention. Fig. 2 is an enlarged detail vertical section on line 2 2 of Fig. 1, showing a partial side elevation and partial longitudinal section of the driving mechanism. Fig. 3 is a cross-section on line 3 3 of Fig. 2. Fig. 4 is a detail view of the walking-beam, and Fig. 5 is a similar view of one of the strap-couplings.

1 in the drawings represents a supporting-frame; 2, 3, and 4, respectively, a driving-shaft, a fan-shaft, and an intermediate power-transmitting shaft journaled therein; 5, 6, and 7, a train of gears connecting the shafts 2 and 3; 8, a belt connecting the shafts 3 and 4, and 9 a balance-wheel on the shaft 6.

On the driving-shaft is a drum or sleeve 10, revolvably mounted on said shaft between two collars 11 and 12, provided with set-screws for fixing them to the shaft, the collar 12 also having a ratchet hub or surface 13, adapted to be engaged by pawls 14 upon the adjacent end of said sleeve 10, the construction being such that when the drum or sleeve 10 is moved in a forward direction the pawls will engage the ratchet-head 13 and impart motion to the shaft and upon the rearward movement of the drum 10 the pawls will ride over the ratchet-teeth and allow the shaft to continue its movement in a forward direction. This construction of ratchet-sleeve and pawls pro-

vides a clutch connection between the fixed 50 sleeve and drum, which allows the latter to have a rocking motion on the drive-shaft and to impart movement to the latter in one direction.

Mounted on a shaft or axle 15, suitably fixed to the frame 1, is a rocker 16, in form of a walking-beam, provided with forwardly and rearwardly extending arms 17 and 18, each of which is provided at its inner end with bearing-shoulders 19 and at its outer end 60 with a holding-lug 20.

Connected to the drum or sleeve 10 and adapted to wind in opposite direction thereon are straps 21 and 22, which are provided at their free ends with couplings 23 and 24, each consisting of a segmentary - curved frame formed of side pieces 25, end pieces 26, and an intermediate cross-bar 27. These couplings 23 and 24 detachably connect the straps 21 and 22 with the two arms 17 and 18, and, 65 as shown in Fig. 2, this connection is made by slipping the free end of the coupling upon the arm until the inner end piece 26 thereof engages the under side of the arm and the adjacent portion of the side pieces 25 engage 70 the shoulders 19 and the cross-bar 27 lies upon the upper surface of the arm and engages the lug 20, whereby the coupling is held from downward and outward movement and yet may be readily disengaged by tilting 75 upward until the cross-bar 27 is removed from engagement with the lug 20, and thus drawing it outward longitudinally from the arm.

The rocker or walking-beam is adapted to be rocked or oscillated by means of an operating-lever 28, which is connected thereto by a pivot-bolt 29, whereby it is adapted to swing laterally toward either of the standards 4. This adaptability of the lever to swing laterally allows the operator to reach out some distance with one hand on either side of the blower to pick up tools or to perform other work while continuing to operate the lever with the other hand, thus avoiding the necessity of letting go the lever and stopping the 80 machine under such contingencies. The rear end of this lever is formed or provided with a counterweight 30, which is adapted to re-

verse the movement of the lever—that is, to restore it to its normal position.

In operation it will be readily understood that by working lever 28 up and down the 5 rocker 16 will be oscillated and in turn impart a vibratory back-and-forth movement to the drum 10, which on its forward movement will be engaged with the ratchet 13 by the pawls 14 and revolve the shaft 2 in a forward direction and on its rearward movement will turn independently of said shaft, as the pawls will ride freely over said ratchet-surfaces. A forward motion of the driving-shaft will be communicated, through the gears 5, 6, and 7, to the 15 shaft 3, and from said counter-shaft motion will be imparted to the fan-shaft 4 through the connecting-belt 8. The fly-wheel or balance-wheel 9 will act by its momentum to keep the shafts revolving in a forward direction.

From the foregoing description, taken in connection with the accompanying drawings, the construction and mode of operation of the invention will be readily understood, and it 25 will be seen that a construction of blower-operating mechanism is provided which may be produced at a comparatively low cost and which may be operated with the expenditure of comparatively slight amount of power.

30 Various changes in the form, proportion, and the minor details of construction may be resorted to without departing from the principle or sacrificing any of the advantages of this invention.

35 Having thus described my invention, what I claim as new, and desire to secure by Letters Patent, is—

1. The combination with a driving-shaft, of a clutch-drum upon the driving-shaft, a clutch 40 connection between said drum and shaft, a

rocker provided with arms, a lever for operating the rocker, straps connected to the drum, and couplings connected to the straps and having detachable interlocking connection with the arms of the rocker, substantially as described.

2. The combination of a driving-shaft, a clutch-drum upon the driving-shaft, a clutch connection between said drum and shaft, a rocker provided with arms, each having a 50 shoulder at its inner end and a lug at its outer end, a lever for operating the rocker, straps connected to the drum, and couplings detachably connecting the ends of the straps to the arms of the rocker, each of said couplings 55 comprising an open segmental frame provided with end pieces and an intermediate cross-bar, said frame adapted to straddle the arm of the rocker and engage the inner shoulder thereof with one of its end pieces bearing against the 60 under side of the arm, and its cross-piece engaging the lug thereof, substantially as described.

3. The combination of a driving-shaft, a clutch-drum upon the driving-shaft, a clutch 65 connection between said drum and shaft, a rocker provided with arms, a counterweighted lever having a pivotal connection with the rocker to swing laterally, straps connected to the drum, and couplings having an interlocking 70 connection with the arms of the rocker, and detachably connecting the straps thereto.

In testimony whereof I have hereunto set my hand in presence of two subscribing witnesses.

CASWELL WATERS.
